UNITED STATES PATENT OFFICE

SAMUEL J. T. PRICE, OF MACON, GEORGIA

ENVELOPE FEEDING MECHANISM

Original application filed January 20, 1926, Serial No. 82,583. Divided and this application filed October 9, 1930; Serial No. 487,563.

This invention relates to envelope feeding mechanism and is a division of my application Serial No. 82,583, filed January 20, 1926, for "Folding, inclosing and sealing machines".

An object of the invention is to provide simple, reliable mechanism for selecting envelopes, one by one, from a stack of envelopes, opening the flaps of the envelopes and conveying them to a position at which letters may be inserted in them.

Referring to the accompanying drawings, which are made a part hereof, and on which similar numerals designate like parts in the several views;

Fig. 1 is a front elevation partly in section, of the machine;

Fig. 2 is a detail of the envelope pick up device;

Fig. 3 is a bottom plan view of the pick up device shown in Fig. 2;

Fig. 4 is a view in edge elevation of the parts as shown in Fig. 3;

Fig. 5 is an enlarged perspective view of the flat pick up finger shown in bottom plan view in Fig. 3 and in edge elevation in Figs. 2 and 4;

Fig. 6 is a front elevation of the envelope container shown in Fig. 1; and

Fig. 7 is a plan view of the container shown in Fig. 6.

The envelopes 10 are held in a container 11 from which they are picked up by mechanism hereinafter described and delivered so as to be positioned between conveying belts 12 and 13 by means of which they are carried to a position at which they have letters inserted in them by mechanism not shown, such for example as that shown in my co-pending application Serial No. 487,564 filed on even date herewith, for "Envelope filling machine".

The envelope container 11 comprises a frame 14 in which is suspended a bottom plate 15. The plate 15 has ears 16 which extend out through slots 17 in the frame. Suspension springs 18 are attached to the ears 16 and suspended from lugs 19 bent out from the frame or secured to it. The tension of the springs is always in a direction to lift the plate so as to keep the top of the pile of

envelopes 10 against a stop plate or ledge 20 at the top of the frame.

A post 21 is mounted on the frame 14, and carries a stop 22 at its upper end for the envelope pickup mechanism shown in Fig. 1, and shown in detail in Figs. 2, 3, 4 and 5. Another stop 23 is fixed to some frame portion of the machine. The pick-up device as shown in Fig. 2 is shown as if the observer were looking at it from the opposite side from the showing of Fig. 1. This pick-up device comprises an arm 24 pivoted on the frame of the machine and having a plate 25 rigidly secured thereto, the securing connecting having a reinforcing or strengthening element 26. On the under side of one edge of the plate 25 is a strip of rubber 27 or other material. One edge of the plate 25 has turned up portions 28 in which are journaled the hexagonal or other angled ends 29 of a shaft 30. A finger 31 is secured upon the shaft 30, this finger having a long end 32 which rests in contact with the friction strip 27 when in closed position as in Fig. 4, and a short end 33 which engages the stop 23 to bring the finger to the closed position as shown in Fig. 2. The finger is moved to open position upon the end 33 coming into contact with the stop 22. The friction bearings 28 engaging the angled ends 29 of the shaft 30 hold the finger 32 in open and in closed position when it has been moved to these positions by the stops 22 and 23, respectively.

In Fig. 1 the upper envelope is shown as having its gummed flap 34 projecting upwardly in position for engagement by the finger 32 when the latter is in the position of Fig. 1 or in the dotted line position of Fig. 2. When the arm 24 is in the dotted line position of Fig. 2 the upper stop 22 engages the short end 33 for opening the finger 32 to receive the gummed flap 34 of the envelope. When the arm 24 moves to the full line position of Fig. 2 stop 23 is engaged and the envelope is grasped by the finger 32, the swinging of the arm further moving the envelope to position it between the conveyor belts 12 and 13, which operate over rollers 35 and 36. The upper roller 36 is reduced at 37 to receive the end of the finger 32. The

arm 24 and the rollers 35 and 36 may be operated by any suitable moving mechanism on the machine to which the device is attached as for example that shown in the co-pending application, of which this is a division. It is here shown as moved by a cam 40 against which it is held by a spring 41. The envelope passes up between the belts and upon emerging from the belts slides up an inclined plate 38 to be deposited on a table 39 when a letter may be inserted in it as by mechanism shown in my co-pending application filed on even date herewith or by any other suitable mechanism. The envelopes 10 may then be transferred to any suitable mechanism and stacked, collected, or otherwise disposed of, such other mechanism forming no part of this invention and hence not described.

20 I claim:

1. In combination, means for supporting a stack of envelopes in position to allow the flap of an envelope to project above the pile of envelopes, means movable to receive an envelope and hold it by the flap, and convey it to a predetermined position, and means for receiving it at the last named place and conveying it to a predetermined destination, said conveying means taking the envelope 25 with the end of the envelope opposite the flap being first engaged and carried forwardly.
2. In combination, means for supporting

a stack of envelopes in position to allow the flap of an envelope to project above the pile of envelopes, means movable to receive an envelope and hold it by the flap, and convey it to a predetermined position, and means 70 for receiving it at the last named place and conveying it to a predetermined destination, said conveying means comprising a pair of belts frictionally engaging the envelope between them and the end of the envelope opposite the flap being first engaged by the conveyer belts.

3. In an envelope pick-up and conveyor device an envelope support, means for maintaining a pile of envelopes on said support 80 with the top of the pile at the same level regardless of the number of envelopes in the pile, means for conveying envelopes to a predetermined place, means for selecting the envelopes one by one from the pile and transferring them to the conveying device, said last named means comprising an arm pivoted at one end and having a pick-up finger at the other end, means for swinging the arm, and having means comprising a pair of belts frictionally engaging the envelope between them 85 with the end of the envelope opposite the flap being first engaged, said pick-up finger being opened at one limit of the swing of the arm and closed at the other, and frictional means 90 for holding the finger in open or closed position when moved to this position.
